CLAIM

The ornamental design for a light module for linear LED as shown and described.

DESCRIPTION

FIG. 1 is a perspective view of the light module for linear LED showing our new design;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top elevational view of FIG. 1; and,

FIG. 7 is a bottom elevational view of FIG. 1.

In the drawings, the broken lines illustrate portions of the light module for linear LED in which the design is embodied and form no part of the claimed design.
